UNITED STATES PATENT OFFICE.

HENRY R. BEHRENS, OF WORCESTER, MASSACHUSETTS, ASSIGNOR TO
ARTHUR M. TAFT, OF SAME PLACE.

LEATHER-STRETCHING MACHINE.

SPECIFICATION forming part of Letters Patent No. 446,847, dated February 24, 1891.

Application filed March 5, 1890. Serial No. 342,713. (No model.)

To all whom it may concern:

Be it known that I, HENRY R. BEHRENS, of the city and county of Worcester, and State of Massachusetts, have invented certain new and useful Improvements in Leather-Stretching Machines; and I do hereby declare that the following is a full, clear, and exact description thereof, reference being had to the accompanying drawings, forming a part of this specification, and in which—

Figure 1 represents a top or plan view of a leather-stretching machine embodying my improvements. Fig. 2 is a side view thereof with the main shaft in cross-section, looking in the direction indicated by arrow *a* in Fig. 1. Fig. 3 is an end view of the machine, looking in the direction indicated by arrow *b* in Fig. 1. Fig. 4 is a vertical longitudinal section of said machine, looking in the direction of arrow *a*; and Figs. 5 and 6 are a longitudinal and transverse section, respectively, upon an enlarged scale, of part of the tension-regulating mechanism, hereinafter more fully described.

My invention is designed more especially for stretching leather to be used for belting; and it consists in an improved construction and arrangement whereby the leather is caused to be rubbed or "racked" back and forth with short reciprocating movements over and in contact with suitable racking-frames to stretch said leather; also, whereby the leather may be gradually drawn forward to keep it taut under a strong tension during said stretching operation, and said forward tension discontinued after the leather has been properly stretched, all by a continuous and automatic operation, as hereinafter more fully set forth.

To enable others skilled in the art to which my invention appertains to better understand the nature and purpose thereof, I will now proceed to describe it more in detail.

In the drawings, *A* represents the main frame for supporting the racking-frames *B* *B'* and the various operating parts of the machine. The frame *B* is made stationary, being in practice secured in any well-known way to the main frame *A*, while the frame *B'* is fitted to slide longitudinally in said main frame,

being provided upon each side with a horizontal longitudinal flange *c*, (see dotted lines, Fig. 3,) adapted to fit in correspondingly-shaped grooves *d* in the main frame. It is operated by means of an eccentric *e* on the main shaft *C* through the long pawl *f*, connected at one end with said eccentric and at its other end adapted to engage with the ratchet-teeth *g* on the under side of the frame. It is kept in engagement with said teeth by a suitable spring *h*, secured to a stationary bearing *h'* and adapted to force the end of the pawl against the teeth. The frame is held against back action when the pawl *f* is moved back to engage with each succeeding notch or tooth in pushing the frame forward by means of a stationary spring-pawl *i*, also adapted to engage with the teeth *g*. The purpose of said forward feed movement of frame *B'* is to maintain at all times the same relative distance from the front end of the frame to the front fastening-point of the leather, so that said leather may be rubbed close up to the fastening during the stretching operation hereinafter described. Said stretching operation is performed by rubbing the leather under strong tension and down pressure back and forth longitudinally with short reciprocating movements over and in contact with the upper edges of a series of transverse blades *j*, secured in the frames *B* *B'*, said action being similar to that which would be produced if a person were stationed at each end of the leather, pulling back and forth with the leather taut, in opposite directions, with the ends below the level of the transverse bearings.

The leather *D* is fastened at each end over the racking-frames *B* *B'* in suitable clamp devices *E* and *F*, arranged on the large sliding frame or carriage *G*, fitted to slide longitudinally in suitable guideways in the main stationary frame *A*. Said carriage *G* is operated forward and back longitudinally, to produce the aforesaid reciprocating movements in stretching the leather, by means of a large eccentric *H*, secured on the main shaft *C*, through the eccentric-strap *H'*, fitted over said eccentric, and the eccentric-rod *I*, connected at one end with said strap and at its opposite end with a cross-piece or other suitable bear-

ing I' on the carriage G. Said eccentric II not only operates the carriage G, but also, through said carriage and suitable connections hereinafter described, the mechanism 5 for pulling forward the front end of the leather to keep said leather taut and under strong tension during the stretching operation.

The clamping device E consists of the slide-block E' and eccentric-shaft E², while the clamp device F consists of the slide-block F', swivel-block F², (pivoted at its front end to said slide-block by a vertical bolt n,) and an eccentric-shaft F³, similar to shaft E². Said 15 eccentric-shafts are fitted to turn in suitable bearings E³ E⁴ on carriage G and operated in practice by means of suitable crank-levers.

In securing the leather in the clamps the ends thereof are inserted between the eccentrics E² F³ and blocks E' F², and said eccentrics then turned to clamp or grip said ends, as is shown in Fig. 4 of the drawings.

Both clamp devices E and F are made adjustable, being fitted to slide in suitable longitudinal guideways or grooves k l, respectively, formed upon each side in the upper parts of each end of carriage G. They may be held in position after adjustment by passing pins m vertically through openings m' in 30 the carriage and the slide-blocks of said clamps.

During the stretching operation the holding-pins for holding the front clamp F are removed to permit said clamp to be forced 35 forward, as hereinafter described.

In stretching short pieces of leather part of the transverse blades j at the rear or outer end of the stationary frame B are removed, as required, and in order that the clamp may 40 be kept in the same relative position to the blades (which are each made a little higher from the outer ends of the frame toward the center of the machine) the guide-grooves k are inclined upward (see Fig. 4) to correspond 45 with the general upward incline of the series of blades j at this end of the machine.

The purpose of pivoting the front clamp F so as to swivel, as aforesaid, is to permit the same to automatically adjust itself to any unevenness in the leather produced by the 50 stretching operation.

The slide-block F' is moved forward with short and regular intermittent movements to keep the leather drawn taut under strong tension while being stretched by the return movements of carriage G, each back movement of the carriage causing the teeth of a large ratchet-wheel J, mounted thereon, to come in contact with the end of a horizontal pressure-rod K, thereby turning said ratchet-wheel one tooth forward, and in consequence also moving said slide-block F' one tooth forward through the shaft L, pinion M, internal segment-gear N, external segment-gear O, and 55 rack P. The ratchet-wheel J and pinion M are secured on the horizontal transverse shaft L, while the segment-gears N O are secured

to the horizontal transverse shaft Q, both of which shafts are fitted to turn in suitable bearings on carriage G. Rack P is secured 70 to the under side of slide-block F', and the segment-gear O is arranged to engage therewith, while the pinion M engages with the other segment-gear N, as is fully shown in Fig. 4 of the drawings.

The horizontal pressure-rod K is fitted to slide longitudinally in suitable bearings K', formed upon or secured to frame A, and a constant yielding forward pressure is imparted thereto by a weight S through suitable 80 connections engaging with the rear end of said rod. The forward movement of the rod is controlled by collar or stop o, adapted to bear against one of the bearings K' or some other fixed point on the machine. In this instance said connections consist of the long horizontal lever p, pivoted at its forward end to frame A and carrying the weight S at its opposite end, the vertical link q, pivoted at 85 its lower end to the central part of said long lever p and at its upper end to the outer end of the horizontal arm of a crank-lever r, and said crank-lever, pivoted at its angle to a bearing on frame A, and whose upper end has a bearing against the end of rod K. (See Figs. 95 1 and 2 of the drawings.) By this construction and arrangement it will be apparent that the rod K is held with a strong forward pressure, while at the same time it is susceptible 100 of being pushed back by an opposite pressure when said pressure is greater than the counter-pressure produced by the weight S.

The purpose of said mechanism is to provide means whereby the longitudinal tension upon the leather during the stretching operation 105 may be automatically governed, so that said leather may not be improperly stretched.

In stretching a piece of leather, as D, it is first secured in position as taut as possible by hand with the slide-frame B' close up to the stationary frame B and the segment-gears N O in the positions shown in Fig. 4. The power is then applied in the usual way, which causes the carriage G to be moved back and forth to rub the under side of the leather 110 against the transverse blades j, at the same time causing the front clamp device F, as well as the slide-frame B', to be moved forward with short intermittent movements, as and for the purpose previously described.

The operation of rubbing and pulling with gradually-increased longitudinal tension upon the leather is continued until it is stretched as much as it will bear without injury thereto, when said tension is discontinued and the stretched leather simply drawn back and forth over the transverse blades j without further stretching until the machine is stopped. The tension is discontinued when the resistance of the leather in stretching is sufficient to 125 overbalance the counter-pressure produced by the weight S through its connections previously described. At this stage in the stretching operation, when the ratchet-wheel J comes 130

in contact with the rod K the latter is pushed back by the return movements of carriage G, consequently forcing back the upper end of crank-lever r and lifting the weight S through 5 said lever r and the other connections, as is indicated by dotted lines in Fig. 2.

The ratchet-wheel and the parts connected therewith are held against back action when the forward end of the pressure-rod K is disengaged from the teeth of said wheel by a 10 spring-pawl J', arranged upon a suitable bearing on the carriage, which is also adapted to engage with the teeth of the wheel. The forward feed movements of slide-block F' may 15 be varied more or less by changing the position of the stop o on rod K and turning the longitudinal screw o' in or out of the rear end of said rod, and the duration of the stretching operation may also be varied by moving 20 the weight S in or out on its supporting-lever p. This adjustment is of advantage in treating different grades and sizes of leather.

The weight S may be held against longitudinal movement on its supporting-lever by 25 extending a flange S' up therefrom provided with a longitudinal opening for said lever, and with a transverse opening to receive an eccentric-bolt S², adapted to bear upon the top of the lever, and having a handle S³ for 30 turning the same to grip or release said weight to and from the lever.

A leather-stretching machine constructed as herein set forth and shown is strong and effective in use and requires but little attention in repairs and from the attendant in 35 running the same, while at the same time a superior grade of work is produced, the leather being thoroughly and uniformly stretched throughout its length close up to the end 40 fastenings.

Although the construction and arrangement herein shown and described are preferable in practice, I do not limit myself thereto, but reserve the right to make such modifications therein as may be desirable under 45 different circumstances in carrying out the principle of my invention.

What I claim as new, and desire to secure by Letters Patent, is—

50 1. A leather-stretching machine comprising, in combination, the following elements: a stationary frame secured to the main frame and a slide-frame fitted to slide longitudinally in said main frame, said frames being arranged end to end lengthwise of the machine and each having a series of transverse blades projecting upward therefrom, over which the leather may be rubbed, mechanism for holding the leather by its ends in contact with the 55 top edges of said transverse blades and for pulling said leather back and forth with short reciprocating movements in a taut condition and with a strong down pressure against said blades, mechanism for feeding forward the 60 slide-frame aforesaid with short intermittent movements and for holding the same against back action, mechanism for feeding forward

the device to which the front end of the leather is fastened with short intermittent movements, also for preventing back action thereof, mechanism for controlling the speed and duration of the last-described forward feed movement, and suitable supports for the various operating parts, whereby the leather may be properly stretched by a continuous 75 and automatic operation, substantially as set forth.

2. In a leather-stretching machine, the combination, with the main supporting-frame and its actuating-eccentric operatively connected therewith, of a longitudinally - reciprocating carriage fitted to slide in said frame, having suitable slide-blocks mounted on each end thereof, upon which are in turn mounted clamp devices for holding the ends of the 85 leather to be stretched, the transverse rack-blades over which the leather is rubbed, and mechanism connected with one of the slide-blocks for feeding it forward to stretch the leather, substantially as set forth. 90

3. In a leather-stretching machine, the combination, with the main supporting-frame, of a longitudinally-reciprocating carriage fitted to slide in said frame and having clamp devices at each end for holding the ends of the 95 leather to be stretched, a stationary frame secured to the main frame, and a slide-frame arranged end to end lengthwise of the machine, and each having a series of transverse blades projecting up therefrom, said slide-frame being fitted to slide longitudinally in said main frame and having short intermittent forward movements imparted to it, substantially as set forth. 100

4. In a leather-stretching machine, the combination of the main frame with the stationary frame B, secured thereto, and the slide-frame B', fitted to slide longitudinally therein, and having means for moving the same forward with short intermittent movements, said 105 frames B B' being arranged end to end lengthwise of the machine and each provided with a series of transverse blades j, substantially as set forth.

5. In a leather-stretching machine, the combination of the main frame with the frame B', fitted to slide longitudinally in said main frame and having notches or teeth g upon its under side, the eccentric e on shaft C and its connections with the slide-frame, said shaft, 110 and a suitable spring-pawl for preventing back action of said slide-frame, substantially as and for the purpose set forth. 115

6. In a leather-stretching machine, the combination of the main frame with the carriage G, fitted to slide longitudinally therein and having the clamp devices E F at each end thereof for holding the ends of the leather, the eccentric H on shaft C and its connections with said carriage, said shaft, the stationary frame B, and frame B', having short intermittent forward movements, said frames being arranged end to end lengthwise of the machine and each having a series of transverse 125 130 blades, substantially as set forth.

- blades *j*, substantially as and for the purpose set forth.
7. In a leather-stretching machine, the combination of frame *A*, carriage *G*, fitted to slide longitudinally therein and having reciprocating movements imparted to it from an eccentric on the main shaft through suitable connections, the adjustable slide, clamp device *E*, mounted on the rear end of the carriage, the adjustable swivel slide-clamp device *F*, mounted on the forward end of said carriage and having a rack *P* upon its underside, and slide-rod *K* on the main frame, operatively connected with said rack *p*, substantially as and for the purpose set forth.
8. In a leather-stretching machine, the main frame *A*, frame *B*, secured thereto, and frame *B'*, fitted to slide in said main frame, also having short intermittent forward movements imparted thereto from an eccentric on the main shaft through suitable connections and held against back action by a suitable stationary spring-pawl, in combination with carriage *G*, fitted to slide longitudinally in frame *A* and having reciprocating movement imparted to it from an eccentric on the main shaft through suitable connections, the adjustable slide-clamp device *E*, mounted on the rear end of the carriage, the adjustable swivel slide-clamp device *F*, mounted on the forward end of said carriage and having a rack *p* upon its underside, and slide-rod *K* on frame *A*, operatively connected with said rack, substantially as and for the purposes set forth.
9. In a leather-stretching machine, the combination of the adjustable block *F'*, fitted to slide longitudinally in carriage *G* and having the swivel-clamp, mounted thereon, also having a rack *P* upon its underside, with the segment-gears *O N* and pinion *M*, shafts *Q L*, fitted to turn in suitable bearings in carriage *G*, ratchet-wheel *J*, its spring-pawl, and slide-rod *K* on the main frame, substantially as and for the purpose set forth.
10. In a leather-stretching machine, the ratchet-wheel *J*, mounted on carriage *G*, having a suitable holding-pawl and operatively connected with a clamp device *F*, substantially as described, in combination with the adjustable slide-rod *K*, having a suitable stop, and weight *S*, operatively connected with said rod, substantially as and for the purpose set forth.
11. In a leather-stretching machine, the combination of the weight *S*, having an up-turned flange provided with a longitudinal opening to receive its supporting-lever *p* and with a transverse opening to receive an eccentric-bolt *S'*, with said lever and eccentric-bolt, the latter being provided with means for turning the same, substantially as and for the purpose set forth.

HENRY R. BEHRENS.
